UNITED STATES PATENT OFFICE.

ADAM E. FISHER AND JAMES A. STORM, OF ST. LOUIS, MISSOURI.

WASHING MACHINE.

Application filed October 25, 1923. Serial No. 670,667.

To all whom it may concern:

Be it known that we, ADAM E. FISHER and JAMES A. STORM, citizens of the United States, residing at St. Louis, State of Missouri, have invented certain new and useful Improvements in Washing Machines, of which the following is a specification.

This invention is an improvement upon a certain type of percolating or flushing clothes-washing machine or device, as exemplified in United States Letters Patent No. 1,423,823, of July 25, 1922, to John T. Wood on wash boiler attachments. Clothes washing devices of this type are provided with a steam forming chamber in some part of the structure, usually at the bottom and adapted for positioning immediately over a fire, and with perforated percolating tubes leading from this chamber through which the hot water and steam are forced by the action of the expanding steam formed in the steam chamber. This type of percolating device is very efficient in washing clothes, but the percolating effect thereof is entirely dependent upon the actual formation of steam in the steam chamber. In other words, the water must be heated to the boiling point in order to render the device effective. It is the object of the present invention, therefore, to provide an improvement upon this type of washing device, wherein a pump and returning pipe line are employed for forcing the streaming of the water through the perforated tubes or the like, independently of the action of heat on the water, or whether the water is hot or cold. Another object is to provide such improvement in a form which will enable the operation and use of the washing device through the employment of the agency of heat alone, as usual, or through the agency of the pump alone, or through the operation of both the agency of heat and the agency of the pump, working together, as may be desired.

This invention is for use in combination with a washing device 1 of the percolating or flushing type described, the same being provided with a false or raised bottom 2 surrounded by a perpendicular marginal flange or strip 3, and seated within an ordinary wash boiler 4, whereby a steam-forming chamber 5 is formed between the raised bottom 2 and the bottom of the boiler. Percolating tubes 6 lead from this chamber 5, the same being seated in and through bases

6' and these tubes are pierced with a plurality of percolating holes 7. The combined apparatus is set over a fire, and water is filled in the boiler. Steam forms within the chamber 5 and forces hot water out through the perforated tubes 6 with a streaming or percolating action in the well known manner; and when soap or other detergent is added to the water, the cleansing effect upon clothes placed in the container is very effective.

It is sometimes desirable, however, when washing very delicate fabrics or fabrics colored with very fadeable colors, that this streaming or percolating action be had and maintained without the agency of heat, or with a degree of heat considerably below the boiling point; and it is the purpose of this invention to accomplish this object.

In the drawing—

Figure 1 is an end view of the complete apparatus, a section of the boiler being broken out to show the arrangement of the flushing device inside;

Figure 2 is a top or plan view, the lid of the boiler being removed;

Figure 3 is a longitudinal, vertical section;

Figure 4 is a detail of the tube and pipe connection;

Figure 5 is an enlarged detail of the threaded lock sleeve for the tube and pipe connection;

Figure 6 is an enlarged detail of one of the threaded plugs or closures for the base of the percolating tubes;

Figure 7 is an enlarged detail of one of the threaded closures for the delivery and receiving ends of the pipe line;

Figure 8 is an end elevation of the apparatus as mounted upon a stove, a section of the boiler being broken away to show the interior arrangement, the exterior pipes being removed and the pipe openings being closed with caps.

In carrying out this invention for the type of washing apparatus described in the forepart of this specification, a tube and pipe connecting joint 8 is provided, the same being in this instance, for convenience, in the form of a Y. This joint is threaded at 9 at the end of its stem 10, and its branches 11 are permanently connected at the points 12 with the bases 6' of the percolating tubes 6 and communicate through said bases with the interior of the tubes 6. The branches 11

rest upon the raised bottom plate 2, and the threaded stem 10 passes off laterally adjacent one side of the boiler 4. A joint 13 is permanently seated through the side of the boiler 4 in alignment with the stem 10, and both ends of the joint 13 are threaded, as shown at 14. A threaded nipple 15 is likewise permanently seated through the side of the boiler adjacent the joint 13. A returning pipe line 16 is provided and has incorporated therein a rotary pump 17 for forcing a water circulation, and any conventional means may be employed for driving the pump. The ends of the pipe line 16 are threaded at 18 and are releasably connected by threaded sleeves 19 to the joint 13 and nipple 15, respectively. A similar threaded sleeve 19 serves to releasably join the inner end of the joint 13 with the stem 10 of the connecting joint 8. The bases 6' are threaded interiorly at the lower points 20, and threaded plugs 21 are fitted thereinto, thus serving as removable closures therefor. Threaded caps 22 are provided for sealing the outer ends of the joint 13 and the nipple 15 when the forced circulation of water is not employed. A stove 23 is provided for heating the water in the boiler.

This apparatus may be operated with water below the boiling point by screwing the plugs 21 into the bases 6', and connecting the stem 10 of the joint 8 with the inner end of the joint 13 with a sleeve 19 and similarly connecting the ends of the pipe line 16 with the outer end of the joint 13 and the nipple 15 by sleeves 19. In this arrangement the pump forces a circulation. It may be operated by heat alone in usual manner, by removing the three sleeves 19 and the plugs 21 and sealing the outer ends of the joint 13 and the nipple 15 by two caps 22. Or, both heat from the stove, and the pump may be employed simultaneously by connecting the pipe line and removing the base plugs.

While we have herein described a certain specific manner and method of constructing and assembling the elements of our invention, it is understood that we may vary from the same in minor details, not departing from the spirit of our invention, so as best to construct a practical device for the purpose intended, as defined in the appended claims.

We claim:

1. In combination with a water boiler

and a percolating device mounted therein adapted to percolate water under the action of heat, the said percolating device having normal water intakes and water outlets; means for forcing a percolation of the water independent of the action of heat, said means comprising a returning pipe line leading from and back into the boiler; a pump incorporated in the pipe line; connecting joints for connecting the percolating device with the delivery end of the pipe line; means for closing the said connecting joints; sleeves for releasably connecting the connecting joints with the delivery end of the pipe line; and means for closing the normal water intakes of the percolating device.

2. In a combined apparatus of the kind described and embodying a water boiler, and a percolating device in the boiler, the said percolating device having normal water intakes and water outlets, means auxiliary to and independent of the action of heat for forcing water through the percolating device, said means comprising a pipe line leading from and back into the boiler; means for releasably and operatively connecting the delivery end of the pipe line with the percolating device; means for releasably closing the normal water inlet of the percolating device; and means for forcing a circulation of water through the pipe line.

3. In a combined apparatus of the kind described and embodying a water boiler, and a percolating device in the boiler, the said percolating device having normal water intakes and water outlets, means auxiliary to and independent of the action of heat for forcing water through the percolating device, said means comprising a pipe line leading from and back into the boiler; means for forcing a circulation of water through the pipe line; means for releasably and operatively connecting the delivery end of the pipe line with the percolating device through an opening in the percolating device additional to the normal water inlet thereof; means for closing the said normal water inlet; and means for closing the additional opening of the percolating device when the normal inlet thereof is open.

In testimony whereof we affix our signatures.

ADAM E. FISHER.
JAMES A. STORM.
